[57] CLAIM

The ornamental design for a flat toothpick dispenser card, as shown and described.

DESCRIPTION

FIG. 1 is a front elevational view of a flat toothpick dispenser card showing my new design, the rear being a mirror image;

FIG. 2 is a top plan view thereof, the bottom view being a mirror image;

FIG. 3 is a right side elevational view thereof, the left side being a mirror image;

FIG. 4 is a cross-sectional view thereof, on an enlarged scale, taken on line 4—4 of FIG. 1;

FIG. 5 is a cross-sectional view thereof, on an enlarged scale, taken on line 5—5 of FIG. 1; and

FIG. 6 is a cross-sectional view thereof, on an enlarged scale, taken on line 6—6 of FIG. 1.

FIG. 1
